(57) **CLAIM**

The ornamental design for a stand for TV receiver, as shown and described.

DESCRIPTION

FIG. 1 is a perspective view of a stand for TV receiver, showing my new design;

FIG. 2 is a front view thereof;

FIG. 3 is a rear view thereof;

FIG. 4 is a side view thereof;

FIG. 5 is another side view thereof;

FIG. 6 is a top plan view thereof;

FIG. 7 is a bottom plan view thereof;

FIG. 8 is another front view in which a TV receiver in broken lines is provided to illustrate an example environment; and, FIG. 9 is another front perspective view in which a TV receiver in broken lines is provided to illustrate an example environment.

The broken lines showing of portions of the stand for TV receiver in the figures and the TV receiver in FIGS. 8 and 9 are included for the purpose of illustrating environmental structure and form no part of the claimed design.
